UNITED STATES PATENT OFFICE.

JOHN J. JOHNSTON, OF BOSTON, MASSACHUSETTS.

FIRE-ESCAPE.

SPECIFICATION forming part of Letters Patent No. 722,110, dated March 3, 1903.

Application filed October 16, 1902. Serial No. 127,604. (No model.)

To all whom it may concern:

Be it known that I, JOHN J. JOHNSTON, a citizen of the United States, residing at Boston, in the county of Suffolk and State of Massachusetts, have invented certain new and useful Improvements in Fire-Escapes, of which the following is a specification.

My invention has for its object to simplify and improve the construction of that description of fire-escapes in which one end of the life-rope is attached to a weighted piston or plunger arranged within an upright pneumatic tube, the rope passing over a pulley or pulleys at the upper end of the tube and being provided at its free end with means for attachment to a cage or basket or to a sling or strap fastened to the person desiring to descend to the ground.

With this object in view my invention consists in the combination, with an upright pneumatic tube, a weighted plunger or piston movable therein, and a rope or chain passing over a pulley or pulleys and having one end secured to said piston, of a rope-clamping mechanism adapted to be automatically set or operated to lock the rope when its free end arrives at its normal raised position opposite the window, whereby said free end or the cage or basket attached thereto will be held immovably in place until released by the person desiring to descend.

My invention also consists in certain other novel combinations of parts and details of construction, as hereinafter set forth, and specifically pointed out in the claims.

In the accompanying drawings, Figure 1 is a perspective view of the upper portion of my improved fire-escape, parts being removed to show the interior construction. Fig. 2 is a vertical section through the center of my fire-escape drawn on a reduced scale. Fig. 3 is a view of a building having two of my fire-escapes applied thereto. Fig. 4 is a horizontal section on the line 4-4 of Fig. 1. Fig. 5 is a detail to be referred to. Fig. 6 is a vertical section of the yielding stop.

In the said drawings, A represents the front wall of a building to which my improved fire-escape is applied.

B is an upright air-tube which is closed at its bottom and extends from the ground to the window-casing C, where it is provided

with a curved head or top piece a, preferably made to swivel on the main upright portion of the tube by means of a joint 10, so that it 55 may be brought close to the window, if desired, or swung away when not required for use. The tube B is securely held in its proper vertical position by means of straps or clips 12, as shown in Fig. 3, and is closed just above 60 the joint 10 by a diaphragm or partition 14, provided with a small central aperture 15.

Within the tube B is a weighted piston or plunger D, Fig. 2, provided with suitable packing to cause it to closely fit the interior 65 of the tube, and to this piston is secured one end of a life rope or cable 16, which extends up through the aperture 15 in the diaphragm 14, thence over a series of pulleys 18, arranged within the arched head a, and down 70 through the open end thereof, where the outer or free end of the rope is provided with a yielding stop E, having at its bottom a hook 20 or other suitable means for attachment to a cage, basket, or other device or to a belt or 75 sling fastened to the body of a person desiring to escape in the event of fire. The stop E consists of a cylindrical box or casing, preferably composed of two parts b c, fitted one within the other and secured together by 80 screws, as shown in Fig. 1, the inner portion c being provided at its bottom with an eye d to receive the hook 20; but the hook may be made integral with the part c, if desired. Within the inner portion c is a piston or head 85 f, to which the end of the rope is secured, and between said head f and the top of the portion c, through which the rope passes, is a strong helical spring g, adapted to yield when the weight of a person desiring to escape 90 is applied thereto for a purpose to be hereinafter described. The piston f is provided with vertical grooves 17, as shown in Fig. 4, in which fit guide-ribs 9, projecting from the part c, a suitable stop 8, Fig. 6, 95 being provided to limit the downward movement of the parts b c when under heavy strain. As the person descends the weighted piston D is drawn up within the tube B, the air escaping slowly through the aperture 15 in the diaphragm 14 and being consequently compressed, thereby preventing a too-sudden descent of the person to the ground. As 100 soon as the person has reached the ground

and is freed from the rope the weight D will immediately descend in the tube and return the free end of the rope to its normal elevated position, as shown in Fig. 1. The tube B is 5 provided with an aperture 21, located at such distance from its lower end that the weight D will cover and close said opening just before reaching the termination of its descent, thus producing an air-cushion to check the 10 descent of the weight and prevent any shock or concussion when it reaches the ground, while when the weight is resting at the bottom of the tube it will uncover the opening 21, thereby admitting the air to the tube as 15 required.

In order that the free end of the rope or the cage or basket which may be attached thereto may be held immovably in place until the person is ready to descend, I provide 20 a rope-clamping mechanism, which will be automatically applied by the rope itself on reaching the limit of its upward movement, as will now be described.

Immediately above the joint 10 the arched 25 head a is enlarged to form a chamber 22, the front of which is closed by a removable plate 23, Fig. 5. Within this chamber is a stationary vertical abutment 24, having serrations on the face next to the rope 16, which 30 runs parallel therewith. On the opposite side of the rope is an inwardly and upwardly inclined abutment 25, having a smooth face, and between the rope and the abutment 25 is placed a vertically-sliding clamping-wedge 35 26, having serrations on its vertical face, which lies next to the rope, and having a pin or stud 27, which engages a slot 28 in a horizontal hand-lever 29, fulcrumed at 30 and having its outer end forked to embrace the 40 rope 16, whereby as the rope is raised to its normal elevated position the stop E will be brought into contact with the outer end of the lever 29, thus raising it and causing the wedge 26 by its contact with the inclined 45 abutment 25 to engage the rope, which will then be gripped between said wedge and the serrated abutment 24 and immovably locked in such manner that any downward strain on the free end of the rope will tend to clamp it 50 with additional force. Consequently as long as the lever 29 is supported by the stop E in the position shown in Fig. 1 the end of the rope, or the cage or basket attached thereto, will be held immovably in place to allow a 55 person desiring to escape convenient opportunity to connect himself with the rope or get into the car or basket attached thereto before it commences to descend. As soon as the weight of the person is applied to the stop 60 E it will be drawn down against the resistance of the spring g, leaving sufficient space between the top of the stop E and the hand-lever 29 to allow the latter to be depressed, as is necessary to relieve the rope-clamp, 65 when the person desiring to escape will descend with the rope slowly and with perfect safety to the ground, and on the release of

the rope it will be immediately raised by the weight D to its normal elevated position and be automatically locked by the clamping 70 mechanism previously described ready for another person, if required.

I do not wish to limit myself to the precise construction of the rope-clamping mechanism herein shown and described above or to 75 that of the yielding stop at the free end of the rope, as variations may be made in the same to produce similar results without departing from the spirit of my invention.

The above-described fire-escape is designed 80 to provide means of escape for one floor or story only of a building, there being one of these fire-escapes for each floor, as shown in Fig. 3.

What I claim as my invention, and desire 85 to secure by Letters Patent, is—

1. A fire-escape comprising an upright pneumatic tube, a weighted piston movable therein, a rope passing over a pulley or pulleys at the upper end of said tube and having one end fastened to said piston, a yielding stop secured to the free end of the rope and provided with means for attachment to a person or object, a rope-clamping mechanism provided with an outwardly-extending 90 hand-lever embracing the rope outside the said tube and adapted to be lifted by the contact therewith of said yielding stop to automatically clamp the rope and lock the same in its normal raised position ready to receive 100 the person desiring to escape.

2. In a fire-escape, the combination with an upright pneumatic tube and weighted piston or plunger movable therein, and a life-rope passing over a pulley or pulleys at the 105 upper end of said tube and having one end secured to said piston, of a rope-clamping mechanism provided with an outwardly-extending lever embracing the rope outside the tube and a yielding stop at the free end of 110 the rope, said stop on reaching the end of its upward movement acting on the clamping-lever to raise the same and thereby automatically lock the rope and hold it in its normal raised position, and said stop being also 115 provided with means for attachment to a person or object and being adapted to be carried down independently of the rope by the weight of the person attached thereto sufficiently far 120 below said clamping-lever to permit of its being depressed to unlock and release the rope when the person is ready to descend.

3. A fire-escape comprising an upright pneumatic tube, a weighted piston or plunger movable therein, a life-rope passing over 125 a pulley or pulleys and having one end secured to said piston, a rope-clamping mechanism consisting of a casing having a stationary serrated abutment, a stationary smooth-faced inclined abutment opposite 130 thereto, an outwardly-extending brake-lever embracing the life-rope outside said tube, and a serrated wedge movable longitudinally between the said abutments and connected

by means of a slot and pin with said lever, whereby the rope is clamped when the said lever is raised, a yielding stop at the free end of the rope adapted to contact with and raise 5 the lever to clamp the rope when at the end of its upward movement, said stop consisting of a cylindrical easing provided at its lower end with means for attachment to a person or object and having a piston to which the 10 free end of the rope is attached, and a spring between said piston and the upper end of the casing through which the rope passes, said

spring yielding to permit the casing to be carried down by the weight of a person applied thereto, out of contact with the clamping lever, whereby the latter is left free to be depressed to unlock and release the rope when the person is ready to descend. 15

Witness my hand this 14th day of October, A. D. 1902.

JOHN J. JOHNSTON.

In presence of—

P. E. TESCHEMACHER,
J. E. MALONEY.
